MICROPHONE TRANSDUCER HOUSING

Jerry O'Brien, 33 Pamrapo Ave.,
Jersey City, N.J. 07305

Filed Mar. 25, 1974, Ser. No. 454,223

Term of patent 14 years

Int. Cl. D14—03

U.S. Cl. D26—14 J

FIG. 1

FIG. 2

FIG. 4

FIG. 3

FIG. 1 is a perspective view of a microphone transducer housing showing my new design;

FIG. 2 is a top plan view thereof;

FIG. 3 is a rear view thereof; and

FIG. 4 is a side view thereof.

I claim:

The ornamental design for a microphone transducer housing, as shown and described.
